Berthold, Kenwally

UNITED STATES PATENT OFFICE.

PETER HARDMAN, OF WILLIMANTIC, CONNECTICUT, ASSIGNOR TO THE AMERICAN THREAD COMPANY, OF JERSEY CITY, NEW JERSEY, A CORPORATION OF NEW JERSEY.

TWISTING MACHINERY.

Application filed December 9, 1920. Serial No. 429,386.

To all whom it may concern:

Be it known that I, PETER HARDMAN, a citizen of the United States, residing at Willimantic, county of Windham, State of Connecticut, have invented a certain new and useful Improvement in Twisting Machinery, of which the following is a full, clear, and exact description.

The present invention relates to machines employed in the manufacture of cordage and has special reference to thread twisting machines of the type employing a thread pulling head.

An object of the invention is to provide novel means in a machine of this character for effectively preventing undue strain being placed on the thread during the twisting operation.

Another object of the invention is to provide novel means in a machine of this character for regulating the degree of tension placed on the thread.

With these and other objects in view, the features of the invention consist in certain constructions, arrangements and combinations of parts hereinafter described and claimed, the advantages of which will be obvious to those skilled in the art.

The following is a description of an embodiment of my invention, reference being had to the accompanying drawings, in which,

Fig. 1 shows a side elevation of a twister head embodying my invention;

Fig. 2 is an end elevation of the feed rolls and support;

Fig. 3 shows an end elevation of one of the pulling heads forming part of my invention;

Fig. 4 shows a side elevation of my invention, partly in section; and,

Fig. 5 shows the parts composing the friction drive used in embodying my invention.

Referring more particularly to the drawings, Fig. 1 shows a twister head of old form with my invention applied thereto, my invention being capable of being applied to any twister heads of this general type.

The twister head shown, generally speaking, consists of a spindle 1 carried by a sliding frame 2 mounted upon a slide bar 3. This sliding frame is provided with a pin 4, which works in a slot 5 in a traverse cylin-

der 6 upon a shaft 7 driven by a worm gear 55 and worm 9, which in turn is driven by a sprocket chain 10 from a shaft 11, which is geared by a worm gear 11' and worm 12 to the hollow shaft 13 carrying the flier 14. Upon the spindle 1 is mounted the ordinary sleeve 15 driven by a slip pulley 16, the driving friction of which is due to its being held between plates 17, 17', the former of which is pressed toward the pulley by a spring 18 which can be adjusted by the adjusting nuts 19. 20 is the bobbin upon which the thread is to be wound, the same being removably secured to the plate 17 by the headed stud 21. Mounted upon arms 22 extending from the frame of the machine are the feed rolls 23 and 24 geared together by gears 25 and 26. The upper roll is carried by arms 27 pivoted at 28 so that it, with its gear, can be swung away from the roll 23 in order to permit the threading of the feed rolls. The roll 23, together with its gear 25, is driven by a gear 29 which meshes with a gear 30 on the shaft 31, which shaft carries a sprocket wheel 32 driven by the sprocket chain 33 80 from the sprocket 34 upon the shaft 11.

The mechanism thus far described is an old mechanism familiar to those skilled in the art, with the exception that the arms 22 are a little longer than those heretofore used, in order to permit the introduction of the features embodying my invention.

With this old form of mechanism a plurality of threads 35 from suitably mounted bobbins was passed between the feed rolls 90 23 and 24, after having first been passed through a moistening bath 36 and after passing through the feed rolls passed over a guide 37 and through a condenser 38. From the condenser 38 the yarn to be 95 twisted was passed in a straight line through the hollow spindle shaft 13 to a sheave or a pulley 39 carried by the flier 14, thence passed to similar sheaves 40 and 41 from the latter of which it was delivered 100 directly to the bobbin 20, being wound on the bobbin by the rotation of the flier. The bobbin is made to reciprocate longitudinally at the necessary rate by the action of the traverse cylinder 6, and the shaft 13 carrying the flier being provided with a pulley 42 is driven by a belt 43 from any convenient source. The sleeve 15, upon which the

bobbin 20 is mounted is driven by another belt 44 from the same source so that the two belts 43 and 44 would have a fixed ratio to one another.

- 5 In the apparatus when thus used the tension due to the straight strand of yarn between the condenser 38 and the sheave 39 was due to the fact that the bobbin 20 revolves at a different rate from that of the flier 14, this being brought about by the ratio of the pulleys driving and being driven by the belts 43 and 44 respectively. The tension was further modified by the fact that there was a friction drive between 15 the pulley 16 and the sleeve 15, such that if the drag on the pulley due to the tension of the yarn exceeded a certain amount there would be sufficient slip to prevent the yarn from being overstrained or broken.
- 20 In this old construction the tension of the yarn being twisted, as the mass on the bobbin 20 increased, was constantly diminished on account of increasing leverage so that the tension when the bobbin 25 was nearly full was very considerably less than when the winding began. This was a serious defect, since it produced a variation in the product so that if the yarn was properly twisted at one stage of the 30 winding of the bobbin it would not be properly twisted in other stages of the winding of the bobbin.

Furthermore, the section of the yarn which was being twisted at any one time was 35 necessarily a long section extending from the condenser 38 to the pulley sheave 39. This resulted in a liability to produce an uneven twist resulting in what is known as "runny" or corkscrew yarn.

- 40 In attempts to eliminate this defect, pulling heads have been provided. In the construction shown a pulling head is mounted on the forward end of the hollow spindle 13 which consists of a frame 45 having a base-plate 45 and a bearing plate 46 both formed integral with a connecting member 47, the base plate being provided with a central thread guide 48 and the bearing plate being provided with a central 50 thread guide 49 in alignment with the axis of the spindle 13. Mounted in the plates 45 and 46 are two shafts 50 each carrying on its rear end a gear 51 and in its intermediate portion a grooved roll 52. The gears 51 are 55 operatively connected with the spindle 13 so that as the thread is twisted during the rotation of the spindle a pull is exerted on the thread by the rolls 52.

The parts of the machine described in the 60 foregoing may be and preferably are of well known commercial construction. In the prior machines, however, the driving gears 51 of the pulling rolls 52 are positively connected with the spindle 13 and in such prior 65 constructions it has been found that the pull

ing devices are liable to either place an undue strain on the thread during the twisting operation, or else not a sufficient amount of strain to produce the best results. To overcome this disadvantage of the prior constructions I have in the machine illustrated in the drawings means for regulating the degree of tension placed on the thread by the thread pulling device. As shown the connection between the gears 51 and the spindle 70 13 comprises a friction driving device constructed and arranged to enable the pulling device or rolls 52 to be retarded with relation to the spindle 13 upon an excessive strain being placed on the thread by the devices. Also, the friction driving device has provision for adjustment to vary the degree of tension on the thread required to retard the operation of the pulling device. This connection between the gears 51 and the 75 spindle 13 comprises a double gear, one member 53 of which engages both of the gears 51 while the other member 54 engages a frictionally driven gear wheel 55 mounted upon a fixed stud 56. The gear 55 is driven 80 by the spindle 13 through a friction drive located between the two. This friction drive comprises a gear 57 mounted upon the fixed stud 56 which drives the gear 55 through friction plates 59 and 60, the latter being integral with the gear 55 and the former 59 being movable axially relatively thereto. This plate 59 is provided with a sleeve 61 which fits over a sleeve 62 integral with the gear 55, the sleeve 61 being connected with the sleeve 62 by a spline 63 so as to revolve therewith. Between the gear 57 and the plates 59 and 60 are two leather washers 64. Lock-nuts 66 are screw-threaded on the hollow shaft 62 of the gear 55 and a spring 105 washer 65 is interposed between the nuts 66 and the friction plate 59. The gear 57 is driven by a gear 67 carried by the spindle 13. As the gear 67 differs in diameter from the gear 54, the gears 55 and 57 differing 110 from each other in an inverse ratio from the gears 54 and 67, a differential action is secured. As shown, the gear 67 is made slightly smaller in diameter than the gear 54, the result of this arrangement being that 115 when the spindle 13 is in motion the gear 54 always moves with relation to the spindle provided there is no slip of the gear 57 with relation to the gear 55. With this construction it will be apparent that by 120 properly adjusting the lock-nuts 66 that upon a strain being placed on the thread in excess of the desired amount the operation of the pulling device will be retarded with relation to the operation of the spindle 13, 125 and thus the tension placed on the thread by the thread pulling device may be regulated as desired.

As will be evident to those skilled in the art, my invention permits of various modi- 130

fications without departing from the spirit thereof or the scope of the appended claims.

What I claim is:

1. In a twisting machine, a tubular spindle, a pulling head thereon comprising a frame carrying receiving and discharge guides in line with the axis of said spindle and rotatable pulling means located between said guides, in combination with means for 5 rotating said pulling means relatively to said frame and a friction drive for said last-named means constructed and arranged to enable the operation of said pulling means to be retarded with relation to said tubular 10 spindle upon an excessive strain being placed on the thread.

2. In a twisting machine, a tubular spindle, a pulling head thereon comprising a frame carrying receiving and discharge 20 guides in line with the axis of said spindle and rotatable pulling means located between said guides, in combination with a sleeve rotatably mounted on said spindle and geared to said rotatable pulling means, a 25 stationary shaft eccentric to said spindle, a wheel rotatably mounted thereon and geared to said sleeve, said wheel being connected by gearing to said spindle so as to be rotated thereby, and a friction drive between said wheel and spindle.

3. In a twisting machine, a tubular spindle, a pulling head thereon comprising a frame carrying receiving and discharge guides in line with the axis of said spindle 35 and rotatable pulling means located between said guides, in combination with a sleeve rotatably mounted on said spindle and geared to said rotatable pulling means, a stationary shaft eccentric to said spindle, 40 a wheel rotatably mounted thereon and geared to said sleeve, said wheel being connected by gearing to said spindle so as to be rotated thereby, a friction drive between said wheel and spindle, and means for ad-

45 justing said friction drive.

4. A twisting machine of the class described having, in combination, a twisting device, a thread pulling device, means for driving said devices normally in timed relation comprising a friction driving means 50 for the pulling device constructed and arranged to enable the operation of the pulling device to be retarded with relation to the twisting device upon an excessive tension being placed on the thread, and a take-up mechanism for the twisted thread.

5. A twisting machine of the class described having, in combination, a twisting device, driving mechanism therefor, a thread 60 pulling device, connections between said devices for driving the pulling device normally in timed relation to the twisting device comprising a friction driving means constructed

and arranged to enable the operation of the pulling device to be retarded with relation 65 to the twisting device upon an excessive tension being placed on the thread, and a take-up mechanism for the twisted thread.

6. A twisting machine of the class described having, in combination, a twisting 70 device, driving mechanism therefor, a thread pulling device, connections between said devices for driving the pulling device normally in timed relation to the twisting device comprising a friction driving means 75 constructed and arranged to enable the operation of the pulling device to be retarded with relation to the twisting device upon an excessive tension being placed on the thread, said friction driving means having 80 provision for adjustment to vary the degree of tension on the thread required to retard the operation of the pulling device, and a take-up mechanism for the twisted thread.

7. A twisting machine of the class described having, in combination, a shaft, a thread twisting device carried by the shaft, a thread pulling device mounted on the shaft and capable of rotation with relation to the shaft, driving connections producing 90 relative motion between the shaft and pulling device comprising a friction driving device for enabling the operation of the pulling device to be retarded with relation to the shaft when the tension becomes excessive, 95 means for driving the shaft, and a take-up mechanism for the twisted thread.

8. A thread twisting machine of the class described having, in combination, a thread twisting device, a thread pulling device, 100 means for driving said devices normally in timed relation comprising a friction driving means for the pulling device having provision for adjustment to regulate the degree of tension placed on the thread by the pulling device, and a take-up mechanism for 105 the twisted thread.

9. A twisting machine of the class described having, in combination, a spindle, a thread twisting device mounted on one 110 end of the spindle, a thread pulling device mounted adjacent the other end of the spindle and having a plurality of rotatable pulling means, and means for driving said rotatable pulling means comprising a gear 115 loosely mounted on the spindle and operatively connected with said rotatable pulling means, a second gear carried by the spindle, a shaft arranged parallel with said spindle, gears mounted on said shaft operatively en- 120 gaging said two first mentioned gears, respectively, and means comprising a friction driving device having provision for adjustment for operatively connecting the gears mounted on said shaft.

PETER HARDMAN.
